No. 818,953.

PATENTED APR. 24, 1906.

J. G. GOTTLIEB.
OBSTETRICAL INSTRUMENT.
APPLICATION FILED DEC. 4, 1905.

UNITED STATES PATENT OFFICE.

JOHN G. GOTTLIEB, OF FESSENDEN, NORTH DAKOTA.

OBSTETRICAL INSTRUMENT.

No. 818,958.

Specification of Letters Patent.

Patented April 24, 1906.

Application filed December 4, 1905. Serial No. 290,249.

To all whom it may concern:

Be it known that I, JOHN G. GOTTLIEB, a citizen of the United States, residing at Fes-
senden, in the county of Wells and State of
5 North Dakota, have invented certain new
and useful Improvements in Obstetrical In-
struments, of which the following is a specifi-
cation.

My invention relates to improvements in
10 obstetrical instruments or forceps for veteri-
nary purposes or for use in emergency in
childbirth.

It has for its object, among other things, to
provide for the removal of the fetus or young
15 in normal condition or alive, or by "piece-
meal" when necessary, with perfect immu-
nity from injury to the patient or risk to life,
and to do this with facility and effectiveness.

To these ends said invention consists of
20 certain structural features substantially as
hereinafter fully disclosed, and particularly
pointed out by the claims.

In the accompanying drawings, illustrating
the preferred embodiment of my inven-
25 tion, Figure 1 is a perspective view thereof in
open position. Fig. 2 is a broken vertical
longitudinal section showing more fully the
removable teeth, cutters, or "fangs" for use
30 in connection with the jaws of the instrument
or forceps. Fig. 3 is a broken side or edge
view of the jaws, having fitted thereon rub-
ber or leather caps for using the instrument
35 for the removal of the fetus or young in nor-
mal condition or alive. Fig. 4 shows disas-
sembled views of the teeth, cutters, or fangs
carried by the jaws of the instrument or for-
ceps. Fig. 5 is a cross-section taken through
40 said jaws.

In carrying out my invention I employ
40 two jaw members 1 1^a, having integral han-
dles 2 2^a, suitably passed one through the
other and pivoted together, as well under-
stood, and adapted at their free ends, prefer-
ably as shown at 2^b 2^c, for convenience in ob-
45 taining the requisite purchase thereon in
manipulating the instrument or forceps.
These jaws are preferably of what may be
termed "goosebill" shape for presenting a
broad surface to the parts to be operated
50 upon or grasped and are of unequal length,
one being much shorter than the other, as
disclosed, and are adapted to be equipped
with teeth, cutters, or fangs 3 3^a. Said jaws
55 are more or less depressed or dished to render
them more effective than would otherwise be
the case in securing a gripping action there-

between and the object engaged. The cut-
ters, teeth, or fangs 3 3^a, having screw-
threaded extensions or shanks removably ap-
plied in any number, singly, two, or three, 60
for an operation to the jaws, as aforesaid, are
bevel-edged and produced in various forms
and sizes to render them effective for readily
mutilating, crushing, cutting, or gripping the
bones, the flesh, or the tissue, as may be re- 65
quired in event it should be necessary to
remove the fetus or young by piecemeal.
For facilitating this purpose these cutters or
teeth are adapted, by suitably turning them,
to be changed as to their relative angle of 70
presentation according to the requirements
of the work to be performed. It will be ap-
preciated that said cutters or teeth are
brought into use only in cases of emergency,
as well understood, in order to save life at the 75
expense of the destruction of the fetus or
young.

In the ordinary use of the instrument or
forceps, as in effecting the removal of the fe-
tus or young normally, rubber or leather 80
"caps" or covers 4 are slipped upon the jaws
thereof, as shown, the purpose of which is ob-
vious.

The instrument is highly effective in ac-
tion, and by means thereof the required ob- 85
stetrical operation may be performed with
facility and entire immunity from injury to
the patient or risk to life, as aforesaid.

It is obvious that my forceps or instrument
is effective equally for use upon animals, as 90
well as upon persons, as above intimated, and
for normally disposing the fetus or young in
event the position of the latter may become
distorted or out of the natural.

I claim—

1. An obstetrical instrument, comprising
95 handle-equipped pivoted-together jaw mem-
bers, oblong in the direction of their lengths
and dished or depressed in their opposed ef-
fective surfaces.

2. An obstetrical instrument, comprising
100 handle-equipped pivoted-together jaw mem-
bers, oblong in the direction of their lengths
and dished or depressed in their opposed ef-
fective surfaces, and having the latter pro-
vided with cutter or fang receiving openings.

3. An obstetrical instrument, comprising
105 handle-equipped pivoted-together jaw mem-
bers, oblong in the direction of their lengths
and dished or depressed in their opposed ef-
fective surfaces and having the latter
equipped with cutters or fangs, a number be-

ing arranged upon each jaw member and those upon one jaw member alternating the cutters upon the other jaw member.

4. An obstetrical instrument, comprising
5 handle-equipped pivoted-together jaw mem-
bers, oblong in the direction of their lengths
and dished or depressed in their opposed
effective surfaces and having the latter
equipped with cutters or fangs removably in-
10 serted therein, those of one jaw member al-

ternating the cutters of the other jaw mem-
ber, said cutters or fangs having laterally-ex-
tended cutting edges.

In testimony whereof I affix my signature
in presence of two witnesses.

JOHN G. GOTTLIEB.
